Application August 24, 1945, Serial No. 612,519

14 Claims. (Cl. 200—112)

(Granted under the act of March 3, 1883, as
amended April 30, 1928; 370 O. G. 757)

1

This invention relates in general to an electric switch and in particular to a mercury-oil switch which is adapted to operate in exposed positions and in positions subject to motion and vibration.

In many cases, such as for example on board ships and other moving equipment, it is desired to have a quietly operating electric switch to complete and break electric circuits without undue arcing, which can be controlled from a master switchboard which in turn takes up a minimum of space. The need for such a switch is perhaps most clearly brought out in the construction and operation of small naval vessels such as destroyers, destroyer escorts and submarines.

It is an object of this invention to provide a mercury-oil type of electric switch that is adapted to operate with a minimum of arcing.

It is another object to provide an electric switch that is adapted to be worked by a small-sized switchboard located at a distance from the main switch.

It is an additional object to provide an electro-magnetically operated mercury-oil-type electric switch.

It is a further object to provide an electric switch of the mercury type that can be installed and operated independently of position and external motion.

Further objects and advantages of this invention, as well as its construction, arrangement and operation, will be apparent from the following description and claims in connection with the accompanying drawing, in which

Fig. 1 is a cross sectional view of a mercury oil switch according to one embodiment of this invention.

Fig. 2 is a diagrammatic view of the switch shown in Fig. 1 showing the relative location of parts in the "open" position.

Fig. 3 is a view similar to that of Fig. 2 showing the relative location of parts in the "closed" position.

In the figures of the drawing, there is shown an electric switch generally designated 11 contained within an outer casing or container generally designated 12. This container 12 comprises a cylinder 13, a top or cap 14 and a base 15. The container 12 is constructed of a liquid-tight electric insulator, such as for example an insulating fiber, an electric-insulating plastic or the like.

Optionally, the cap 14 can be adapted to be screwed on to the top of the cylinder 13, or alternatively it can be integrally fixed thereon.

Near the center of the cylinder 13 are a pair of 5 metallic rings or contacts 16 and 17 mounted within the cylinder, optionally by being molded therewithin, and having their inner surfaces in line with the inner surface of the cylinder. These rings 16 and 17 are positioned apart a suitable 10 distance to prevent sparking therebetween at the voltage under which the switch is adapted to operate, and are preferably located near the center of the cylinder 13.

Within the container 12 and adjacent to either 15 end thereof are two double solenoids generally designated 18 and 19. These solenoids are mounted by conventional means such as supports 20. Each solenoid comprises an inner half 21 and 22 and an outer half 23 and 24.

20 Slidably mounted within the cylinder 13 near its lower end is a piston 25 having a piston rod 26 connected thereto through insulating washer 26a, the rod 26 extending from the lower portion of the piston and projecting within the lower 25 solenoid 19. On the outer surface of piston 25 and bearing against the inner wall of the cylinder 13 are a plurality of piston rings 27. The piston 25, piston rod 26 and optionally the rings 27 are constructed of a non-magnetic metal such 30 as aluminum, a non-magnetic stainless steel, or the like.

35 Integrally attached to piston rod 26 is an armature 28 which optionally is a rod of similar cross section to the piston rod 26. This armature is suitably constructed of a highly magnetic material such as for example soft iron or a ferromagnetic alloy.

Similarly, near the upper end of the cylinder 13 is a piston 29 adapted to slide within cylinder 40 13, and having a piston rod 30 connected thereto by means of insulating washer 30a and having a piston ring 27 on its outer surface. Optionally, this upper piston 29 is divided into a piston body 31 and a piston face 32. The piston body 31 and 45 the piston rod 30 are suitably constructed of a non-magnetic metal such as for example aluminum or an insulating non-metal, whereas the piston face 32 is constructed of an electric insulating material such as for example an oil-resisting 50 thermo-setting resin. The piston face 32 can be

integrally attached to the piston body 31 or alternatively it can be separated therefrom as shown in Fig. 1 by an air or oil space 33. When such an air or oil space 33 is provided there can optionally be used a ball check valve 34 and a valve spring 35 to permit the upward passage of liquid or vapor through the piston 29. Under normal conditions of operation this ball check valve can be omitted; however, when the switch is to be used with unusually high voltages and there is danger of electric arcing notwithstanding the construction and operation of this switch, it may then be desirable to provide this valve to permit escape of mercury vapor which is generated during the arcing process.

Integrally attached to the piston rod 30 and projecting within upper solenoid 18 is an upper armature 36 of similar construction and design to lower armature 28.

On the inner surface of the cylinder 13, between the upper electrical contact 16 and the lower contact 17, is an annular piston wedge seat 32a comprising a wedge-shaped ring projecting from the surface of the cylinder. The piston face 32 is adapted to rest against this wedge seat thereby effectively sealing off the upper electrical contact 16.

Also located on the inner surface of the cylinder are two broad rings 25a and 29a of a metallic substance such as for example aluminum, steel or the like. These rings 25a and 29a are adapted to provide a smooth hard surface to maintain contact with the sliding piston rings 27 thereby preventing undue wear of the walls of the cylinder and enabling the piston rings to maintain a liquid-tight sliding joint with the cylinder walls.

By virtue of the two pistons, 25 and 29, the cylinder is divided into three chambers: an upper chamber 37, a lower chamber 38 and an inner or mercury chamber 39. Connecting the upper chamber 37 and the lower chamber 38 is a conventional by-pass tube 40 which permits passage of liquid or vapor between the two chambers.

In order to permit easy servicing and repairing of this switch there are optionally provided a drain valve 41 at the bottom of the cylinder 13, a safety vent 42 at the top of the cylinder and a screw plug and vent 43 located in the cylinder wall adjacent to the cap 14.

In Figs. 2 and 3 are shown a diagrammatic outline of the switch described in connection with Fig. 1 indicating the position of parts in the open and closed state of the switch. In the switch as shown in Figs. 2 and 3, the lower chamber 38, the by-pass tube 40 (not shown), and the upper chamber 37 are substantially filled with oil or an oil-like substance up to oil-level line 45. The middle chamber 39 of the switch is partly filled with mercury to the level indicated by the mercury level line 46. At the top of the upper chamber 37, above the oil-level line 45, is a small quantity of air or other gas to provide for expansion or contraction of the contents of the cylinder.

In Fig. 2, which shows the open position for the switch, the lower armature 28 is positioned within the outer half 24 of the lower solenoid 19 and accordingly the lower piston 25 is retracted toward the bottom of the cylinder. The upper armature 36, on the other hand, is positioned within the inner half 21 of the upper solenoid 18 and accordingly the upper piston 31 is positioned well within the cylinder with the lower space of the piston face 32 below the upper electrical contact 16 and resting against piston wedge

seat 32a (Fig. 1), thereby sealing off the upper electrical contact 16 from any contact with the mercury contained in the mercury chamber 39.

In Fig. 3, which shows the closed position of the switch, the lower armature 28 is positioned within the inner half 22 of the lower solenoid 19, while the upper armature 36 is positioned within the outer half 23 of the upper solenoid 18, thereby causing the upper piston to be raised above the upper electrical contact 16 and causing the lower piston 25 to be correspondingly raised almost to the level of the lower electrical contact 17. Thus, in the closed position of the switch, both electrical contacts 16 and 17 are covered by the mercury contained in the mercury chamber 39 and thereby are electrically joined.

In the use and operation of this electrical switch the various chambers are filled with oil and mercury as indicated in the drawings and hereinbefore described, and the switch is installed in a suitable location. The inner half 22 of lower solenoid 19 is electrically joined to the outer half 23 of upper solenoid 18 as by conductor 50, and, likewise, the outer half 24 of lower solenoid 19 is electrically joined to the inner half 21 of upper solenoid 18 as by conductor 52. These joined solenoid halves are then electrically connected to a switch 54 positioned on a conveniently located switchboard (not shown in the drawing). When this switch is turned to the "on" position half-solenoids 22 and 23 are energized and when the switch is turned to the "off" position half-solenoids 21 and 24 are energized. Thus the operation of a low-voltage switch on a remotely located switchboard controls the operation of the main switch 11.

When the externally located control switch is turned to the "on" position, pistons 25 and 29 are caused to rise within the cylinder 13 thereby bringing the mercury in contact with both of the electrical contacts 16 and 17. Simultaneously oil passes from upper chamber 37 to lower chamber 38 through by-pass 40 to permit this movement of the pistons. When the control switch is moved to the "off" position this piston and liquid motion is reversed thereby breaking the contact. The presence of the layer of oil on top of the mercury in the mercury chamber causes the electrical circuit to be broken with a minimum of arcing thereby preventing the formation of undue quantities of mercury vapor and preventing undue corrosion of the electrical contacts.

Although this switch has been described as being in a vertical position, it will be seen that the upper piston in its closed position completely seals off the upper electrical contact 16 from the mercury chamber, and therefore this switch can be installed in a vertical or horizontal position and can be subjected to vibration or rocking motion without causing accidental electrical contact.

In repairing and maintaining this switch the following dismantling procedure is used: The screw plug 43 is removed and drain 41 is then opened permitting the oil to drain from the lower chamber 38 and the by-pass tube 40 and to drain partially from the upper chamber 37. The cap 14 is then unscrewed permitting access to the pistons and solenoids contained within the cylinder.

By means of this new mercury-oil switch it is now possible to attain the advantages of quiet operation and compactness offered by the mercury-type switch without the disadvantages normally associated therewith. For example, the

undue arcing normally associated with mercury switches has been eliminated, and possibly of even greater importance, the new switch is independent of position or external motion. The advantage of compactness and convenience of size of the new switch is still further improved by the fact that the switch is adapted to be electrically operated by remote control, permitting the mounting of numerous small master switches on a convenient switchboard maintained in small and crowded quarters.

Modifications and changes can be made in this invention without departing from the spirit and scope thereof as set forth in the appended claims.

For example, the lower piston 25 can be electrically activated to become one of the electric contacts, operationally replacing contact 17. Likewise various other conventional and obvious changes in the structure and operation can be made.

The invention described herein may be manufactured and used by or for the Government of the United States of America for governmental purposes without the payment of any royalties thereon or therefor.

What is claimed is:

1. A mercury-oil electric switch comprising an insulating cylindrical container, a pair of magnetically-operated pistons mounted therein and adapted to propel within the cylinder in mutually opposed directions a body of mercury having a body of oil on its upper surface, one of said pistons having an insulating part adjacent said body of mercury, and a plurality of electric contacts mounted within said cylinder, said insulating part operating to insulate at least one of said contacts from said body of mercury as the latter is moved in a first direction within the container by said one piston.

2. The switch as in claim 1, wherein said one contact is adapted to be electrically joined to said body of mercury as the latter is oppositely moved by the other piston.

3. A mercury-oil electric switch comprising an insulating cylindrical container having two electric contacts mounted within a common straight-line section of said container and insulated one from the other, a pair of opposing pistons mounted within said straight-line section and magnetically operated from either end thereof, a body of mercury and a body of oil positioned between said pistons and adapted to be propelled within said container so that the body of mercury is caused to make and break electrical connection with one of said electric contacts while maintaining electrical connection with the other of said electrical contacts.

4. A mercury-type electric switch comprising an insulating cylinder, two electric contacts internally mounted within said cylinder, a lower piston mounted within the cylinder near the lower end of said cylinder and adapted to be magnetically propelled and retracted by a solenoid mounted from the lower end of said cylinder, an electrically insulating upper piston mounted within the cylinder and near the upper end thereof and adapted to be magnetically propelled and retracted by a solenoid mounted from the upper end of the cylinder so as to cover and uncover one and only one of said two electrical contacts, a body of mercury and a body of oil positioned between said pistons and adapted to cover and uncover one of said electric contacts as the pistons are propelled and retracted, while maintaining an electrical connection with the other of said

electric contacts, and a by-pass tube connecting the portions of the cylinder behind the upper and lower pistons respectively and permitting fluid flow therebetween.

5. A mercury-oil switch comprising a cylindrical container, a plurality of electromagnetically-operated pistons mounted therein and adapted for simultaneous operation for propelling in mutually opposed directions a body of mercury contained within the cylinder, and a plurality of electric contacts mounted within said cylinder, at least one of said contacts being positioned to be electrically connected to said body of mercury as the latter is moved within the container by one of said pistons and disconnected therefrom as the mercury is moved by another of said pistons.

6. A mercury-oil switch comprising a cylindrical container, a pair of spaced electromagnetically-operated pistons mounted therein the adjacent faces of said pistons defining, with the side wall of said container, a substantially closed space, a body of mercury within said space and adapted for constrained movement with said pistons, and a plurality of electric contacts mounted flush with the inner wall of said cylinder, at least one of said contacts being positioned to be electrically connected to said body of mercury as it is moved within the container.

7. The switch claimed in claim 6 further comprising means on said pistons and cooperable with said contacts for ensuring a fluid-tight junction between said pistons and contacts.

8. A switch comprising a container having at least two electric contacts mounted therein and insulatingly spaced one from the other, a pair of pistons mounted for movement axially of said container, said pistons being dimensioned to fit snugly within said cylinder and adapted to be magnetically operated from opposite ends thereof, a body of mercury disposed between said pistons and adapted to be propelled within said container by said pistons, whereby the body of mercury may be caused to make and break electrical connection with one of said contacts while maintaining constant electrical connection with the other of said contacts.

9. The switch defined in claim 8 further characterized by stop means in the path of one of said pistons for limiting the amount of travel of said one piston toward said other electrical contact.

10. The switch defined in claim 8 further characterized by electromagnetic means within said container and adapted to be energized for jointly moving said pair of pistons in a unitary direction, and coolant means surrounding said electromagnetic means.

11. An electric switch comprising a tubular container, fluid contact means in said container, a pair of annular contacts mounted flush with the inner wall of said container, piston means defining with said wall an enclosure for said fluid contact means, and means for moving said enclosed fluid contact means selectively to make and break electrical connection between said contacts.

12. An invertible mercury switch, comprising a tubular container, mercury in said container, contacts mounted in the wall of said container, and piston means defining with the container wall an enclosure for confining said mercury, whereby the latter may be moved to make and break electrical connection between said contacts independently of the disposition of said container.

13. The switch as in claim 12, wherein said

piston means comprises a pair of spaced plunger members adjacent the free surfaces of said mercury, and electromagnetic means for each said member for moving the latter in unison.

14. The switch as in claim 12, wherein said piston means comprises spaced movable plunger members with the mercury disposed therebetween, and means defining a vent in one of said members for controlled passage of mercury vapor.
